CHASE ASSEMBLY

Kenneth V. Goodloe, Houston, Tex., assignor to Clarke and Courts Investment Company (Inc.), Houston, Tex., a corporation of Texas

Application December 29, 1955, Serial No. 556,315

10 Claims. (Cl. 101—391)

This invention relates to printer's chases and more particularly to main and adjustable sub chases which latter are adapted to fit within the main printer's chases.

Arrangements wherein the sub chase is adjustable within the main chase are particularly useful in overprinting work. For example, such a device is quite useful in printing checks wherein the variable printing matter such as the bank, account number, check number, etc., is placed on the partially printed checks in a second printing operation. Minute adjustability of the sub chase carrying such matter is quite important for registration purposes. It is also desirable that means be furnished for affording rapid replacement of the type in this sub chase.

In view of the above it is one object of this invention to provide a main chase, a sub chase assembly and a base within the sub chase and which holds the type and is adjustably positioned vertically and horizontally within the main chase.

Another object is the provision of a sub chase having means for locking and unlocking a plurality of portions of independently positioned type by means operated by a single quoin.

It is yet another object of this invention to provide a sub chase assembly wherein one or more lines of type may be removed and replaced with other lines and still maintain correct registration.

These and other objects and advantages of this invention will be more fully understood from the following detailed description when taken in conjunction with the drawing, wherein:

Fig. 1 is a perspective view of the combined main chase and sub chase assembly;

Fig. 2 is a cross-section taken along line 2—2 of Fig. 1 showing the means which engage and hold the type in position in the sub chase;

Fig. 3 is a cross-section taken along line 3—3 of Fig. 1 showing the details of the means for horizontally adjusting the type carrying base within the sub chase;

Fig. 4 is a cross-section taken along line 4—4 of Fig. 1 showing the means for vertically adjusting the sub chase within the main chase;

Fig. 5 is an enlarged horizontal sectional view showing the means for securing the sub chase frame to the vertical adjusting means within the main chase; and

Fig. 6 is an enlarged perspective view of a portion of the sub chase base showing details of an opening and plates adapted to receive and hold the type.

Although the device of this invention has many applications, it is particularly well adapted for the overprinting of check blanks so as to fill in the pertinent data of a more specific nature such as the bank name, check number, city or bank address, name of payer and other similar data. Since check blanks are often printed in sheets containing six check blanks this sub chase arrangement has been made to accommodate such sheets.

Referring to Fig. 1, the main chase 10 comprises top and bottom members 11, 12 and side members 13 and 14

2

secured together to form a rectangular framework. The members 11, 12, 13 and 14 may be made of metal in which case the connections may be produced by welding; however, any other means would be satisfactory. The inner face of each side member 13, 14 has a longitudinal groove 15 extending throughout most of its length.

A sub chase assembly 20 is mounted within the main chase 10. This sub chase comprises a rectangular framework having top, bottom and side members 21, 22, 23 and 24 respectively. The outer face of each side member 23 and 24 has a longitudinal tongue 26 which slidably fits in groove 15 of side members 13 and 14. Thus the sub chase assembly is positioned for vertical sliding motion from top to bottom within the main chase 10. The top and bottom members 21 and 22 of the sub chase each has a longitudinal groove 28 on its inner face.

The sub chase base 30 is generally rectangular in shape and fits within the sub chase framework. The top and bottom edge portions of the base 30 have longitudinal tongues 31 which slidably fit in grooves 28 in the sub chase top and bottom frame members so that the base may move horizontally from side-to-side within the sub chase framework.

The sub chase base 30 carries the type which is to be used, generally in an overprinting operation. As previously mentioned, the sub chase shown is adapted for overprinting sheets which contain six check blanks per sheet. Appropriate openings must be provided in the base 30 to carry type for such printing. In this particular instance the sheet of checks is formed of two horizontal rows of three blanks each, consequently the base 30 is formed to carry type accordingly. For carrying sufficient type to overprint each check blank the base is provided with three openings A, B, and C. The openings A and B are adapted to carry type for printing names and places while opening C is used for numbering the checks. It will be seen that this arrangement of openings A, C, C is used for overprinting each check blank. Therefore the base 30 comprises three sets of columns of type receiving openings, the respective openings A, A; B, B and C, C being in alignment with each other both laterally and vertically. In addition a cut out D is located adjacent the upper portion of the base above each set of column containing openings A, B and C and has a length generally coextensive with that covered by openings A and C.

Of course, the openings A, B and C must have some means for holding the type in locked position. This is accomplished by using plates 32 positioned in the openings and adapted to engage the type. As best shown in Fig. 2 the aligned openings A and B have plates 32 slidably positioned adjacent the top and bottom faces within these openings. In Fig. 6 an enlarged section is shown wherein plate 32 has a lug 34 extending from the end shown and the lug slidably fits into recess 36. The same arrangement is used on both ends of all the plates to prevent their loss and limit their movement.

With the slidable plates in the openings some means is needed for forcing the plates against the type carried in these openings. This is accomplished by means of pins 38 slidably carried in holes 40 extending through the portion of the base between vertically aligned openings to connect same with each other. Actually the pins 38 are slightly longer than the length of their respective holes 40 so that force exerted on the topmost pin at point 42 will progressively lock the type in the openings by causing the type in all of the vertically aligned openings A, B to be successively engaged by their respective plates 32 under the action of the pins 38. Thus it will be seen that a force exerted on pin 38 at 42 by a quoin positioned in opening D will progressively force pin 38 against plate 32 contacting the type which in turn bears against the

adjacent plate and then transmits the force to the next pin until the entire aligned column of type is locked in position.

When the type is of some length two or more series of aligned pins may be used. In the example shown, two columns of pins are used for the openings A, B and one column for openings C.

The advantages of such an arrangement are obvious. Such an arrangement makes it possible to quickly release all of the type by the loosening of the quoins carried in opening D. The third column of openings in Fig. 1 illustrates how the assembly will appear when the type E and quoins 44 are in place.

Although the type is carried in aligned openings it is nevertheless necessary to laterally and vertically adjust all of the type as a unit in base 30 to properly position same for the overprinting operation. The lateral adjustment is achieved by screw means which is best shown in Fig. 3. An appropriate longitudinal slot 46 is formed in sub chase side member 23 and a threaded rod 48 extends transversely through the slot 46 into the side portion of base 30 where it is locked in position by means of a pin 50. A circular nut 52 is threaded on the threaded rod 50 and is positioned in slot 46 so that a portion of the nut will extend beyond the upper surface of area surrounding the slot to afford access to the nut so that it may be rotated to impart lateral reciprocation to the base 30 carried within the sub chase framework.

The vertical adjustment of the type is accomplished by means of a mechanism best shown in Figs. 1, 4 and 5. The adjusting means actually comprises two similar units, one at each end of the top sub chase member 21, consequently only one will be described in detail. Referring to Fig. 1, a connecting rod 54 extends between the top sub chase member 21 and the inner face of main chase top member 11. Referring to Fig. 5, the connecting rod is secured to the sub chase member 21 by threaded engagement with a plate 56 secured to a block 58 appropriately secured to the sub chase top member 21.

As shown in Fig. 4, the upper end 60 of the connecting rod is generally rectangular in cross-section and has parallel slots 63 on opposite faces which are adapted to engage cam means which are to be described in detail. The cam means comprises a pair of spaced parallel bars 62 adapted to ride in parallel grooves 64 in main chase top member 11. The end portions 65 of bars 62 are cut at an angle with respect to the main portions of bars 62 so as to act as the cam means. These portions 65 are secured to a rectangular head 66 of rod 68. The other end portion 70 of rod 68 is threaded and extends through a suitable hole in the main chase framework. A circular nut 72 is threaded on the end portion 70 of rod 68 and is positioned in slot 74 of main chase side member 13. The diameter of the nut is such that a portion will extend beyond the surface of the area surrounding slot 74 so that the nut may be rotated by hand. The slotted portions 63 of the upper connecting rod end 60 slidably fit over the angular bar end portions 65 so that transverse movement of the bars will cause a vertical movement of the connecting rods 54 and the sub chase secured thereto. The bars 62 are held in place in grooves 64 by means of a plate 78 slotted to guide the connecting rod ends 60. As best shown in Fig. 6 the upper end edges of openings A, B and C are chamfered at 80, thereby affording easy access to type in these openings.

It is believed that the foregoing description clearly indicates the mode of operation of the invention, however, it will be summarized briefly. The sub chase 20 is assembled within the main chase 10 after which the main chase members are fastened together at all four corners. The horizontal and vertical sub chase positioning means are operatively mounted and the assembly is ready to receive the type. The type is placed in the openings A, B, C and held there by the locking means actuated by quoins positioned in cutouts D. After this the chase assembly is

placed in the press at approximately the desired location and the sub chase adjusted for correct final alignment after which the printing is performed.

This invention has produced a valuable addition to the printing field, especially with regard to sub chases. The combination of this sub chase with the main chase makes it possible to accurately and rapidly line up type especially in overprinting, where such adjustment is quite critical.

What I claim as my invention and desire to secure by Letters Patent of the United States is:

1. A chase assembly particularly useful in overprinting work, said assembly comprising a main chase having members forming an open frame, a sub chase assembly mounted within the main chase, the sub chase assembly comprising a framework mounted within the main chase for sliding movement in one direction in the plane of the open frame, a type carrying base fitting within the sub chase framework and mounted for movement therein in a direction normal to the said one direction and in the same plane, the base having aligned type receiving openings and a quoin receiving cutout aligned with said openings, the base having holes connecting the aligned type receiving openings and the quoin cutout, type holding means positioned in each opening, means in said holes for engaging the type holding means, said means being actuated by the insertion of a quoin in the quoin cutout to progressively engage the type holding means to lock the type in position in each type receiving opening.
2. The device as described in claim 1 and including means engaging the frame and framework for sliding the sub chase assembly within the main chase.
3. The device as described in claim 2 and including means engaging the framework and base for sliding the base within the sub chase framework.
4. A chase assembly particularly useful in overprinting work, said assembly comprising a main chase having top, bottom and side members secured together to form a rectangle, the inner face of each side member having a longitudinal groove, a sub chase assembly mounted within the main chase and adapted for sliding movement in the groove of the main chase slide members, the sub chase assembly comprising a rectangular framework having top, bottom and side members, said side members each having a tongue adapted to slidably engage the groove in the corresponding main chase side member, the inner face of the sub chase top and bottom members each having a longitudinal groove, a type carrying base member fitting within the sub chase framework, the top and bottom edge portions of the base having tongues adapted to slidably ride in the grooves in the top and bottom sub chase frame members, said base having aligned openings adapted to hold type and cutouts adapted to receive quoins, said quoin cutouts being aligned with the type holding openings, type engaging plates slidably mounted within each type receiving opening, one plate being positioned adjacent the top and bottom face of each opening, said base having a plurality of holes connecting the aligned type carrying openings and the quoin cutouts, pins positioned in the holes connecting the type carrying openings and the quoin cutouts, said pins being somewhat longer than the length of the holes so as to contact the plates mounted in the openings, the pin portion extending into each quoin cutout being adapted for engagement with a quoin which forces the pin into engagement with the plate and which engages the nearest type, in turn contacting the other plate and successive pins, type and plate until all plates are in tight engagement with type to hold the latter in locked position within the base.
5. The device as described in claim 4 and including means for adjustably moving the type receiving base in the grooves of the top and bottom members of the sub chase framework.
6. The device as described in claim 5 wherein the means are adjustably moving the type receiving base in the

grooves of the top and bottom members of the sub chase framework comprises a rod secured to one end of the base, the other end of the rod being threaded and mounted in the adjacent sub chase side member, this side member having a slot through which the rod extends transversely, a nut mounted on the threaded end of the rod and positioned in the slot, rotation of the nut causing a variation in the effective length of the rod between the nut and the side portion of the base thereby laterally moving the base within the top and bottom sub chase members.

7. The device as described in claim 5 and including means for vertically adjusting the position of the sub chase assembly within the main chase.

8. The device as described in claim 7 wherein the means for vertically adjusting the position of the sub chase assembly within the main chase comprises screw actuated cam means, connecting means secured to the sub chase assembly and engaging the same means so that actuation of the cam means results in vertical adjustment of the sub chase assembly.

9. A sub chase particularly adapted for overprinting, said chase comprising a generally rectangular framework, a type carrying base slidably mounted within the framework, said base having aligned type receiving openings and quoin receiving cutouts aligned therewith, quoins adapted for insertion in said quoin receiving cutouts, and type locking means actuated by the insertion of quoins to progressively engage and lock the type in position in each type receiving opening.

- 5 10. A sub chase particularly adapted for overprinting, said chase comprising a rectangular framework having top, bottom and side members, a type carrying base member slidably mounted within said framework, said base having a plurality of aligned type receiving openings, and also having quoin receiving cutouts aligned with the type receiving openings, the base having holes connecting the aligned type receiving openings and the quoin cutouts, pins positioned in these holes, each pin being slightly longer than the length of its hole, a sildable plate mounted in each type receiving opening adjacent the upper and lower faces thereof, so that upon the insertion of a quoin in one of the quoin receiving cutouts the pin contacting the quoin will be pressed outwardly to successively contact the adjacent and connecting pins, plates and type, thereby locking all the type in position within the base.
